DESIGN FOR A WAGON

John Delbert Wheeler, Detroit, Mich., assignor to
American Metalcraft Corporation, Detroit,
Mich., a corporation of Michigan

Application July 22, 1946, Serial No. 131,814

Term of patent 14 years

(Cl. D34—15)

To all whom it may concern:

Be it known that I, John Delbert Wheeler, a citizen of the United States of America, residing at Detroit, in the county of Wayne and State of Michigan, have invented a new, original, and ornamental Design for a Wagon, of which the following is a specification, reference being had to the accompanying drawing, forming a part thereof, wherein:

Fig. 1 is a perspective view of a wagon showing my new design;

Fig. 2, a side elevation; and

Fig. 3, a top plan view.

I claim:

The ornamental design for a wagon, as shown.

JOHN DELBERT WHEELER.
